SLICER WITH ADJUSTABLE BLADE

Carl Dodegge, Maywood, Ill.

Application September 27, 1946, Serial No. 699,895

1 Claim. (Cl. 146—171)

1

This invention relates to slicers, and more particularly to slicers having a blade which is adjustable to control the thickness of the slice to be cut.

It is the primary object of my invention to construct a slicer which is well adapted for slicing various articles such as, among other things, fruits, vegetables, or cheese, and which has an adjustable slicer blade associated therewith in such a manner that it may easily be set so as to control the thickness of the slices to be cut.

Various types of slicers have been heretofore known to the art. However, such slicers have heretofore had several inherent disadvantages such as, for example, that they were relatively complicated in construction, and difficult to operate. It is an object of my invention to provide a slicer which is simple both in construction and operation, and which may be economically manufactured.

Another common disadvantage in slicers heretofore known to the art has been that the thickness of the slice to be cut was controlled by varying the angle at which the slicer blade was set, and that in many instances the slicer would bind during a slicing operation. It is an object of my invention to construct a slicer wherein the slicer blade is associated therewith in such a manner that during adjustment thereof the same angular relationship is maintained between the slicer blade and the body of the slicer.

A further object of my invention is to construct a slicer which is sturdy and reliable in operation and wherein the blade thereof may be quickly and easily moved to a selected cutting position and firmly secured therein.

Other and further objects of the present invention will be apparent from the following description and claim and are illustrated in the accompanying drawing which, by way of illustration, shows a preferred embodiment of the present invention and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claim.

In the drawings:

Fig. 1 is a top plan view of a slicer embodying my invention;

Fig. 2 is a side elevational view of the slicer shown in Fig. 1;

2

Fig. 3 is a sectional view taken substantially along the line 3—3 in Fig. 1; and

Fig. 4 is a sectional view taken substantially along the line 4—4 in Fig. 1.

For purposes of illustration, my invention is shown in the accompanying drawings as embodied in a slicer 10 comprising in general, a base 12, an adjustable slicer-blade supporting unit 14 and handles 16 and 17.

As is best seen in Figs. 1 and 4 the base unit 12 has two substantially vertically extending side walls 19 and 20, the upper end portions of which are interconnected by a substantially horizontally extending upper wall or table top 21.

The slicer-blade supporting unit 14 comprises two substantially parallel sides 23 and 24 having substantially horizontally extending lugs 25 to which a slicer-blade 26, having a cutting edge 26a, is connected by screws 27 or other suitable means. The side members 23 and 24 are spaced apart but are substantially parallel to each other and, when the slicer-blade supporting unit 14 is attached to the base 12, lie inwardly of, but adjacent to the side walls 19 and 20, respectively, and support the slicer-blade 26 in a substantially horizontal position with the cutting edge 26a thereof positioned adjacent to the table top 21.

Substantially parallel elongated slots 29 and 30 are formed in each of the side members 23 and 24. A pin 31 extends through the side wall 19 of the base unit 12 and through the slot 30 in the side member 23, the ends of the pin 31 being flattened or otherwise enlarged sufficiently to retain it in position so as to hold the side wall 19 and the side member 23 together. In a similar manner the side wall 20 and the side member 24 are fastened together by a pin 32 which extends through the side wall 20 and the slot 29 formed in the side member 24.

A bolt 34 having an enlarged head, forming a knurled knob 35, extends through the side walls 19 and 20 of the base unit 12 and through the slots 29 formed in the side members 23 and 24 of the slicer-blade supporting unit 14. A nut 37 is threaded onto the other end of the bolt 34, opposite the knurled knob 35, and a spacer 38 is loosely mounted on the bolt 34 between the side members 23 and 24. The end portions of the spacer 38 extend across the slots 29 in the side members 23 and 24 and provide abutments against which the side members 23 and 24 are pressed when the nut 37 is tightened on the bolt 34, the side member 23 being pressed against the side wall 19 between one end of the spacer 38 and

the knurled knob 35, and the other side member

24 being pressed against the side wall 20 between the other end portion of the abutment 38 and the nut 37, when the nut 37 is tightened on the bolt 34.

The substantially U-shaped handles 16 and 17 are attached to the base 12 by any suitable means such as welding, and project therefrom so that they may be easily gripped by the operator during operation of my novel slicer.

In the operation of my novel slicer 10, the operator grasps the vegetable or other article to be sliced in one hand and, while holding the slicer 10 by grasping either the handle 16 or the handle 17 in the other hand, manually slides the vegetable across the table top 12 against the cutting edge 26a of the slicer blade 26 which, during a slicing operation is positioned above the table top 21 a distance corresponding to the thickness of the slice it is desired to cut.

The slicer-blade 26 may be adjusted relative to the table top 21 to the proper position corresponding to the thickness of slice which it is desired to cut by turning the knurled knob 35 in the proper direction so as to unscrew the bolt 34 from the nut 37 and thereby loosen the engagement of the side wall 19 with the side member 23, and the engagement of side wall 20 with the side member 24, and then sliding the slicer-blade supporting unit 14 on the bolt 34 and the pins 31 and 32 to the proper position so as to place the slicer-blade 23 in the position desired, and then, by turning the knurled knob 35 in the opposite direction, again tightening the nut 37 on the bolt 34 so as to again tightly engage the side members 23 and 24 with the side walls 19 and 20 respectively.

From the foregoing it will be noted that when the slicer-blade 26 is adjusted relative to the table top 21 it moves not only in a vertical direction thereto, but also in a longitudinal direction. This is desirable so that the space between the cutting edge 26a of the slicer-blade 26 and the adjacent edge portion of the table top 21 is always considerably larger than the thickness of the slice which the cutter blade 23 is set to cut so that binding of the slice cut does not occur between the cutter blade 26 and the table top 21.

Also it will be seen from the foregoing that I have provided a novel slicer which the operator

may easily hold during a slicing operation, and also, that I have provided a slicer which may be easily adjusted by a simple operation to cut a slice of the desired thickness from an article which is reciprocated back and forth on the table top 21 by the operator.

Hence, while I have illustrated and described the preferred embodiments of my invention, it is to be understood that these are capable of variation and modification and I therefore do not wish to be limited to the precise details set forth, but desire to avail myself of such changes and alterations as fall within the purview of the following claim:

I claim:

A slicer comprising two substantially vertically extending side walls, a substantially horizontally extending table top attached to said side walls and adapted to support an article to be sliced, two substantially vertically extending side members, each of said side members having a slot formed therein at an angle to the horizontal and the vertical, means for releasably securing said side members to said side walls, said means including a bolt extending through said side walls and said slots in said side members, said side members being slideable on said bolt longitudinally of said slots to an adjusted position relative to said side walls when said means is released from securing relation with respect to said side members, and an elongated slicer-blade attached to and carried by said side members in parallel relation to said table top in both longitudinal and transverse directions.
